UNITED STATES PATENT OFFICE.

WALTER M. STEWART, OF OTTUMWA, IOWA.

STOKER.

1,118,068.

Specification of Letters Patent.

Patented Nov. 24, 1914.

Application filed February 7, 1914. Serial No. 817,333.

To all whom it may concern:

Be it known that I, WALTER M. STEWART, a citizen of the United States, residing at Ottumwa, in the county of Wapello and State of Iowa, have invented certain new and useful Improvements in Stokers, of which the following is a specification.

This invention relates to a mechanical stoker, and the principal object of the invention is to provide a stoker which is so constructed that coal may be fed to any part of the fire box desired, and to so construct the stoker that vibrations will not cause the pipe of the stoker to be broken or bent. Another object of the invention is to so construct the stoker that the feeding elements may be operated by engines of the steam actuated type, one engine being a reciprocating engine and the other being a turbine engine.

Another object of the invention is to provide a stoker which will be comparatively simple in construction and which will have few parts, and thus not be liable to need very much repairing.

Another object of the invention is to so construct the stoker that it will take up a very small amount of space and thus not be in the way.

30 This invention is illustrated in the accompanying drawings wherein—

Figure 1 is a view showing the stoker in side elevation and mounted in an operative position. Fig. 2 is a longitudinal sectional view through the stoker; Fig. 3 is a top plan view of the stoker; Fig. 4 is a sectional view taken along the line 4—4 of Fig. 1; Fig. 5 is a sectional view taken along the line 5—5 of Fig. 1; Fig. 6 is a sectional view taken along the line 6—6 of Fig. 1; Fig. 7 is a sectional view taken along the line 7—7 of Fig. 1.

This stoker is mounted with the rear portion positioned beneath the coal bunker 10 of the tender 11 and the forward portion mounted in the cab 12 of the engine in front of the boiler 13. When the forward and rear sections of the stoker are connected, they form a continuous tube made up of the rear section 14, forward section 15, intermediate section 16, and collar 17 positioned between the forward section 15 and interme-

diate section 16. It will thus be seen that coal which passes into the rear section 14 may be fed into the forward section where 55 it will be engaged by the propeller mounted in the housing 18 and forced out through the forward end of the pipe into the fire box of the boiler. The rear section 14 which is positioned beneath the bunker 10 is supported by the standards 19 which are secured to the floor of the tender by means of bolts 20. A neck 21 extends upwardly from an inlet opening formed in the section 14 at a point intermediate its length and extends into an outlet opening formed in the bottom of the bunker 10 so that coal may pass from the bunker into the section 14. A plunger 22 which resembles a piston is 70 slidably mounted in the rear section 14 and 75 has its inner ends provided with spurs 23 which engage the coal.

In order to operate the plunger 22 there has been provided a driving rod 24 which is pivotally connected with the outer end of the plunger and has its outer end eccentrically connected with a disk 25 rigidly mounted upon a driven shaft 26. This shaft 26 is rotatably mounted in bearings formed at the upper ends of the standards 27 and carries 80 a disk 28 with which the piston rod 29 of the steam engine 30 is eccentrically connected. The valve 31 of the steam engine 30 is operated by means of a rod 32 which is connected with the eccentric disk 33 by 85 means of the collar 34. It will thus be seen that this steam engine will rotate the shaft 26 and cause the plunger 22 to be reciprocated in the section 14. A pipe 35 is provided for conveying steam to the valve 31. 90

The forward section 15 and collar 17 are supported by the standards 36 and are provided with annular ribs 37 which rest in the pockets 38 at the upper ends of the standards 36. A lever or handle 39 is provided so that 95 the forward section and collar may be readily rotated. The feeding propeller 40 is rigidly mounted upon the shaft 41 which leads from a turbine engine mounted in the housing 42 and it will thus be seen that when 100 steam passes through the pipe 43 and rotates the turbine, the feeding propeller will be rotated to feed the coal through the forward section 15. A door 44 is carried by the shaft

45 upon the upper end of which there is secured the handle 46. This handle 46 is connected with a lever 47 by means of a link 48 and it will thus be seen that when the lever 5 is rocked upon its supporting brackets 49, the door will be moved to guide the passage of the coal out of the stoker.

The collar 17 is connected with the forward section 15 by means of a hinge 50 and the forward section is provided with a flange 51 which extends beneath the collar and prevents coal from leaking between the collar and forward section. The intermediate section 16 fits into the collar 17 and is 15 provided with a pin 52 which extends through a slot 53 formed in the collar. The rear end 54 of the intermediate section 16 is flared to form an enlarged mouth which receives the forward end of the rear section, 20 the rear section being held in the mouth 54 by means of the chains 55.

In the operation of this device, the intermediate section 16 is connected with the rear section after the tender has been coupled to the engine, and the forward section is then swung down to the operative position so that the collar 17 will extend into the forward section 15 and the forward end of the forward section will extend through the 30 door-way 58. As the plunger 22 moves in the rear section, coal will be forced through the rear section and through the intermediate section into the forward section. The revolving propeller 40 will engage the coal 35 and force the coal into the forward end portion of the forward section from which it will pass out into the fire box. By turning the forward section by means of the handle 39 and adjusting the door 44 by means of 40 the lever 47, the coal can be directed into any portion of the fire box desired and thus the coal can be evenly distributed. After sufficient coal has been fed to the fire, or when it is no longer desired to use the 45 stoker, the forward section can be tilted back so that it will rest against the tender, and the door 59 of the boiler can be closed. This stoker has been shown applied to a railroad engine and tender but it is obvious 50 that it could be used in the engine room of a factory or other building for conveying coal from the coal bins to the fire box of the boiler or furnace. If it is desired to remove the stoker, the sections of the stoker 55 may be easily removed from the standards and the sections separated. The stoker can then be placed in a comparatively small amount of space or the various parts may be placed in separate receptacles for storage 60 purposes.

I have thus provided a stoker which is very simple in construction and which is not liable to very easily get out of order or become broken. It will also be seen that I

have provided a stoker which will be easy 65 to assemble and easy to take down when desired.

What is claimed is:

1. A stoker comprising a conduit including a rear section provided with an inlet, 70 supporting means for said rear section, a forward section having an open outer end, a collar, said forward section being hinged to said collar and provided with a flange extending beneath said collar when said forward section is in a lowered position, means for supporting said forward section and collar for permitting rotary motion of said forward section and collar, an intermediate section connecting said collar with said rear 80 section, feeding means in said rear section in operative relation to the inlet thereof, feeding means in said forward section, and means to rotate said forward section and collar. 85

2. A stoker comprising a conduit including a rear section provided with an inlet, a forward section, a collar, said forward section being hingedly connected to said collar, an intermediate section extending into 90 said collar, a pin carried by said intermediate section and extending through a slot formed transversely in said collar, the opposite end portion of said intermediate section inclosing the end of said rear section, 95 means for supporting said collar and forward section for permitting rotary motion of the same, feeding means in said rear section and forward section, and means for rotating said forward section and collar and 100 swinging said forward section to a raised position.

3. A stoker comprising a conduit including a rear section, a forward section, a collar hingedly connected to said forward section, an intermediate section having one end portion extending into said collar, means for preventing the withdrawal of said intermediate section from said collar but permitting said collar to rotate upon said intermediate section, the opposite end portion of said intermediate section being flared and inclosing one end of said rear section, yieldable means connecting said intermediate section with said rear section means for rotatably supporting said collar and forward section, means for rotating said collar and forward section and moving said forward section to a raised position, and feeding means in said rear and forward section. 110 115

4. A stoker comprising a conduit including a rear section provided with an inlet, a forward section provided with an outlet, an intermediate section having one end connected with said rear section, a collar connected with the opposite end of said intermediate section, said forward section being 120 125 singly connected with said collar, sup-

porting means for said collar and the forward and rear sections of said conduit, an arm carried by said forward section for swinging said forward section to a raised 5 position, and feeding means in said rear section and forward section.

In testimony whereof I affix my signature in presence of two witnesses.

WALTER M. STEWART.
